UNITED STATES PATENT OFFICE.

WILLIAM M. HALEY, OF ST. LOUIS, MISSOURI.

PENCIL-SHARPENER.

1,201,458.

Specification of Letters Patent. Patented Oct. 17, 1916.

Application filed November 24, 1913. Serial No. 802,702.

To all whom it may concern:

Be it known that I, WILLIAM M. HALEY, a citizen of the United States of America, and a resident of the city of St. Louis and 5 State of Missouri, have invented certain new and useful Improvements in Pencil-Sharpener, of which the following is a specification.

The primary object of this invention is to 10 provide an improved pencil sharpener whereby the pencil is sharpened by the hand that holds the pencil.

Another object is to provide improved means in a pencil sharpener whereby when 15 pressure is brought to bear on a pencil the cutter portion of the pencil sharpener is revolved causing the pencil to be sharpened.

Other and further objects will appear in the specification and be specifically pointed 20 out in the appended claim, reference being had to the accompanying drawings exemplifying the invention, and in which,

Figure 1 is a vertical section taken through this improved pencil sharpener. 25 Fig. 2 is a horizontal section taken on the line II—II, Fig. 1. Fig. 3 is a horizontal section taken on the line III—III, Fig. 1.

Referring by numerals to the accompanying drawings: 1 designates the base portion 30 of this improved device. Formed vertically in said base portion is a bore 2. Normally seated in the upper portion of said bore 2 is the lower end 3 of a spiral shaft 4, said shaft having the spiral groove 5 formed 35 therein. This shaft 4 is held in its normal position by the helical spring 6 which is mounted in the bore 2. The lower end of said spring rests on the bottom of said bore and the upper end bears against a cup- 40 shaped washer 7. The top side of said washer has the depression 8 formed therein, said depression being for the reception of the rounded portion 9 of said shaft 4. Secured to the top of the base portion 1 by 45 screws 10 is a collar 11. Said collar has a lug 12 extending from the inner periphery thereof, said lug being engaged in the groove 5 of the spiral shaft 4.

Formed on the upper end of the shaft 4 is 50 a stud 13. Mounted over said stud and bearing against the shaft 4 is a rubber bumper 14. Mounted on said stud 13 and bearing against the bumper 14 is a cutter head 15, said cutter head having a central conical

opening 16 formed therein. Formed on said 55 cutter head adjacent the lower end thereof is an annular rib 17. Loosely mounted on said cutter head beneath said rib is a plate 18. Said plate is held in position by the collar 19 and is adapted to serve as a hand 60 rest. Formed in said cutter head is a vertical opening 20 which communicates with a conical opening 16. Mounted in said opening 20 is a cutting blade 21.

This improved device is designed so it 65 can serve as a paper weight as well as a pencil sharpener. When it is desired to sharpen or re-point a pencil, the user merely inserts the end of the pencil in the cutter head and presses downwardly on the pencil, 70 the operation being as follows: The pressing down of the pencil against the cutter head causes the shaft 4 to be moved downwardly in the bore 2, and the lug 12 engaging the groove 5 will cause the shaft to be revolved. 75 As the cutter head is secured to the shaft, said cutter head will also be revolved, and the blade 21 will engage the pencil thereby sharpening the point thereof. When the pressure of the hand is released from the 80 cutter head, the spring 6 will lift the shaft 4 to its normal position. The rubber bumper 22 carried by the lower end 3 of the shaft 4 will engage against the under side of the lug 12, thereby cushioning the shock of the 85 vertical uplift of the shaft. In order to relieve some of the pressure from the pencil as the shaft 4 is moved downwardly, the lower portion of the hand can be brought to bear on the plate 18. The rubber bumper 14 90 which is mounted on the upper end of the shaft 4 will engage against the collar 11, thus limiting the downward movement of the shaft.

What I claim is:

A pencil sharpener comprising a spiral shaft, a cutter head secured to one end of said shaft, a pressure plate loosely mounted on said shaft, said shaft adapted to be moved longitudinally, and means in engagement 100 with said shaft for causing said shaft to be revolved when said shaft is moved longitudinally by pressure on said shaft.

WILLIAM M. HALEY.

In the presence of:

M. C. HAMMON,
H. G. FLETCHER.
